(57) **CLAIM**

The ornamental design for a luggage with organizational system, as shown and described.

DESCRIPTION

FIG. 1 is a perspective view of a luggage with organizational system showing my new design in an open configuration; FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

In the drawings, the broken lines represent unclaimed environment subject matter and form no part of the claimed design.
